UNITED STATES PATENT OFFICE.

HOVE THOMPSON BRINKS, OF INDIANA, PENNSYLVANIA.

AUTOMOBILE-HORN.

1,333,703.

Specification of Letters Patent. Patented Mar. 16, 1920.

Application filed June 30, 1917. Serial No. 177,846.

To all whom it may concern:

Be it known that I, HOVE THOMPSON BRINKS, a citizen of the United States, residing at Indiana, in the county of Indiana and State of Pennsylvania, have invented certain new and useful Improvements in Automobile-Horns; and I do hereby declare the following to be a full, clear, and exact description of the invention, such as will enable others skilled in the art to which it appertains to make and use the same.

This invention relates to improvements in signaling devices for motor vehicles, and has for its primary object to provide a horn and means utilizing the exhaust products of combustion from the engine of the motor vehicle to actuate the horn.

Another object is the provision of a conveniently operable controlling means for the horn, whereby the latter may be sounded at the will of the driver of the vehicle.

With these and other objects in view, the invention consists in the novel construction, combination and arrangement of parts as will be hereinafter specifically described, claimed and illustrated in the accompanying drawing, in which:

Figure 1 represents a side elevation of the horn, partly in section, showing fragments of the floor and exhaust pipe of a motor vehicle,

Fig. 2 represents a longitudinal sectional view through the horn in the plane of the vibrating wheel,

Fig. 3 represents a vertical sectional view through the casing in the plane of the main shaft, and

Fig. 4 represents a longitudinal sectional view through the coupling for attaching the horn to the exhaust pipe.

Referring to the drawing in detail, wherein similar reference numerals designate corresponding parts throughout the several views, the numeral 5 indicates a fragment of the exhaust pipe of a motor vehicle, which is connected, in the usual manner, with the engine (not shown) and is arranged under the floor, a fragment of which is designated by the numeral 6.

At a point intermediate the engine and muffler, the exhaust pipe 5 is cut in two and the adjacent ends are slipped into the head of a T coupling 7, the vertically disposed portion 8 of which receives the depending inlet pipe 9 carried by the circular casing, designated generally by the numeral 10.

The casing 10 is constructed in two parts, designated by the numerals 11 and 12, and the adjacent edges of the parts are flanged and bolted together, as indicated at 13. A partition 14 is secured between the flanged edges of the casing sections 11 and 12 and divides the interior of the casing into chambers 15 and 16.

A shaft 17 is journaled concentrically within the casing 10 and supports a bladed wheel 18, arranged in the chamber 15 and having the blades so disposed as to be rotated by the impact of the products of combustion entering the casing through the inlet pipe 9. The products of combustion are exhausted from the casing 10 through an exhaust pipe 19.

A vibrating wheel 20 is supported upon the shaft 17 within the chamber 16 and is provided with a series of ratchet teeth 21 arranged to contact a stud 22 carried by a diaphragm 23, whereby the latter is vibrated during rotary movement of the vibrating wheel 20.

The front portions of the sections 11 and 12 are flared, as indicated at 24, and a horn 25 is bolted, or otherwise secured, as indicated at 26', to the flared end 24 of the casing. The diaphragm 23 is secured in position between the horn and flared terminal of the casing and may be readily removed for repair or replacement by simply removing the bolts 26' which fasten the horn in position.

A valve 26 is rotatably supported in the horizontally disposed portion of the T coupling 7 at a point behind the vertically disposed portion 8 thereof and is adapted to be closed to cause the products of combustion passing through the exhaust pipe in the direction of the arrows in Fig. 4 to flow into the casing 10. A rotary valve 27 is also supported in the vertically disposed portion of the coupling and is designed to control the admission of the products of combustion to the casing. The two valves 26 and 27 are provided with arms 28 and 29, respectively, which are connected with a cable 30 extending rearwardly under a guide pulley 31 and attached at its rear end to a foot pedal 32, which latter is pivotally supported at 33 under the floor 6 of the vehicle and is adapted to be actuated by the foot of the driver to control the operation of the horn. As clearly shown in Fig. 4, the valves 26 and 27 move oppositely, that is to say, the valve 26

is normally opened to allow the products of combustion to pass freely through the exhaust pipe and into the muffler, not shown, while the valve 27 is normally closed to prevent the admission of the products of combustion to the casing 10. However, when the cable 30 is pulled by a forward movement of the upper terminal of the pedal 32, the position of the two valves is reversed, the passage of the products of combustion to the muffler being cut off by the closed valve 26 and the open valve 27 permitting the products of combustion to pass freely into the casing 10 and act upon the bladed wheel 18 to rotate the shaft 17 and vibrate the diaphragm 23 to produce a warning signal.

As suggested in Fig. 1, a cable housing 34 may be secured underneath the floor and extended upwardly to the steering wheel or other part of the vehicle within convenient reach of the hands of the driver. The housing 34 incloses a flexible cable 35, which is attached to the lower terminal of the pedal 32 and provided at its upper end with a button 36, which may be pressed to effect a longitudinal movement of the cable in the housing 34 to actuate the pedal 32 and thus sound the signal.

What I claim is:

30 1. A horn including a casing comprising a pair of sections and a partition arranged between the sections and forming a pair of chambers, a shaft extending centrally through the chambers, a rotor carried by said shaft and arranged within one of said chambers, a toothed wheel arranged on the shaft and disposed within the other cham-

ber and in spaced parallel relation to said rotor, the forward portion of said casing being flared outwardly, a diaphragm secured to the outwardly flared portion of the casing, and having a centrally arranged stud engaging the teeth of said wheel, and means to direct pressure into contact with said rotor.

2. The combination with an exhaust pipe of an explosion engine, of a branch pipe connected to the exhaust pipe, a casing connected to said branch pipe and including a pair of sections and a partition secured between the sections thereby forming a pair of chambers, a shaft extending centrally through the chambers, a rotor arranged on the shaft and disposed within one of said chambers and adapted to be rotated by the exhaust gases from the exhaust pipe, a toothed wheel mounted on the shaft and arranged within the other compartment and disposed in spaced parallel relation to said rotor, a diaphragm carried by the casing and arranged at right angles to said toothed wheel and provided with a centrally arranged stud engaged by the tooth of said toothed wheel, and means to direct the exhaust gases from the exhaust pipe through the branch pipe and into contact with said rotor.

In testimony whereof I affix my signature in presence of two witnesses.

HOVE THOMPSON BRINKS.
